UNITED STATES PATENT AND TRADEMARK OFFICE
CERTIFICATE OF CORRECTION

PATENT NO. : Des. 490,546 S
DATED : May 25, 2004
INVENTOR(S) : Simon Walker

Page 1 of 4

It is certified that error appears in the above-identified patent and that said Letters Patent is hereby corrected as shown below:

The title page should be deleted to appear as per attached title page.

The sheets of drawings consisting of figures 1-6 should be deleted to appear as per attached figures 1-6.

Signed and Sealed this

Sixteenth Day of May, 2006

A handwritten signature in black ink, appearing to read "Jon W. Dudas", is placed within a dotted rectangular box.

JON W. DUDAS
Director of the United States Patent and Trademark Office
